UNITED STATES PATENT OFFICE.

LEWIS WESTERHOUSE, OF FORT SCOTT, KANSAS, ASSIGNOR TO SAMUEL KAUFFMAN,
OF ST. LOUIS, MISSOURI.

PISTON-RING.

1,280,343.

Specification of Letters Patent.

Patented Oct. 1, 1918.

Application filed April 28, 1916. Serial No. 94,200.

To all whom it may concern:

Be it known that I, LEWIS WESTERHOUSE, a citizen of the United States, residing at the city of Fort Scott, county of Bourbon, 5 and State of Kansas, have invented a new and useful Piston-Ring, of which the following is a specification.

This invention relates to piston rings.

An object of the invention is to provide a 10 packing for pistons comprising a ring composed of two overlapping parts of equal width and length and impressed with internal resiliency, whereby they are pressed together to form the ring, each of said parts 15 extending nearly throughout the circumference of the ring and provided with means for engaging the integral connection of the two parts to hold the ends thereof in proper annular alinement.

20 Other objects will appear from the following description of the invention in which reference is made to the accompanying drawings, wherein—

Figure 1 is an elevation of the ring before the overlapping parts have been impressed with resiliency to hold them side by side.

Fig. 2 is an elevation of the ring reversed in which position it is subjected to treatment 25 to provide the necessary resiliency to hold the two parts side by side as stated in the object of invention.

Fig. 3 is an elevation of the ring completed.

35 Fig. 4 is a view looking toward one of the side edges of the ring.

Fig. 5 is a view of a piston having a number of the rings mounted thereon.

Figs. 6 and 7 are elevations showing a 40 ring of a slightly modified construction.

Figs. 8 and 9 are elevations of a ring of another slightly modified construction.

Fig. 10 is a perspective view of a portion 45 of a ring of a slightly different construction.

Fig. 11 is a perspective view of a portion of a ring of still another construction.

The ring is cut from a cylinder of the desired diameter to provide two spaced overlapping parts 1 and 2 united by an integral 50 connection 3, the width of which is equal to the combined width of the parts 1 and 2 when the latter are pressed together. Each of the overlapping parts 1 and 2 extends nearly the entire circumference of the ring 55 while the integral connection 3 extends over

a relatively small part of the circumference of the ring. After the ring is cut from the cylinder it is reversed so that the overlapping parts 1 and 2 are placed in reverse positions as illustrated in Fig. 2. While 60 in this position the ring is subjected to heat to impress therein and impart thereto the necessary formation to produce the resiliency required in order that the two parts 1 and 2 will be pressed together when the ring is 65 turned back to its proper position, as illustrated in Fig. 3.

The end of the part 1 is provided with an oblique engaging shoulder 4 adapted when the ring is compressed within a cylinder to 70 engage under a matching shoulder 5 on the part 3 and thus hold the end of the part 1 substantially in annular alinement with the remaining periphery of the ring, but permitting sufficient relative movement thereof 75 to form close contact with the surface of the cylinder. The shoulders 4 and 5 are formed obliquely relative to the axis of the ring in order to enable the resiliency of the ring to overcome any tendency of adhesion. 80

The end of the part 2 and the adjacent portion of the connecting part 3 are provided with similarly obliquely formed matching shoulders 6 and 7 for like purposes. 85

The ring thus formed is complete and ready to be applied to a piston. As heretofore stated and as illustrated in Fig. 1, when the ring is first cut from the cylinder the parts 1 and 2 are spaced apart. It is necessary that the space between the overlapping parts be closed in order to prevent accumulations of carbon and other substance from becoming lodged within the space; and further in order to prevent the passage of the gas 90 through the space. By providing the overlapping portions with resiliency so that they are pressed together by the internal elasticity of the material in the manner described, the space between the overlapping 100 portions is entirely closed, thus preventing accumulations of carbon or other material from becoming lodged therein and binding the parts together, and the passage of gas through the ring joints is also prevented. 105 The ring is thus enabled to fit within a groove of the proper width in the piston without binding against the walls of the groove as would occur in the case of a ring having its overlapping portions pressed to- 110

gether by the walls of the groove containing the ring. In cases where the overlapping portions are not pressed together they are caused to stick by the accumulations of carbon and the like, thus interfering with the functions of the ring by preventing free expansion and contraction and by enabling the gas to escape through any open spaces which remain. This is essentially true since it is 5 not possible to cut the rings from a cylinder without leaving the overlapping portions separated by a space of equal width with the thickness of the cutting implement. By impressing the overlapping portions with 10 resiliency, so that they are pressed together by the internal elasticity of the material, all of the foregoing objections are overcome. The corners formed at the intersection of the periphery of the overlapping portions and 15 the side walls of the overlapping portions respectively are effective to cut away and remove any deposits which become caught or lodged against the overlapping portions at their abutting edges. In Fig. 5 a number of 20 the rings are illustrated applied to a cylindrical piston 8 of the usual construction and arranged to operate within the cylinder 9 and to transmit power through a piston rod 10 which is connected to the piston by a pivot 25 11 in the well understood manner. The piston is provided with the usual circumferential grooves in which the piston rings are respectively mounted and in which it will be observed that the ring is compressed, so that 30 the engaging shoulders 4 and 6 of the parts 35 1 and 2 are under the corresponding shoulders 5 and 7.

In Figs. 6 and 7 the end of the part 1 is formed with a recess 12 arranged to receive 40 a projection 13 on the connecting portion 3. In this construction the end of the part 1 is formed obliquely to engage upon the oblique wall of the part 3, so that there is no restraint to the expansion of the part 1. The 45 end of the part 2 is formed with a recess 14 adapted to receive a shoulder 15 on the connecting part 3 so that in these and other particulars the ends of the parts 1 and 2 of the ring illustrated in Figs. 6 and 7 are identical. 50 In Figs. 8 and 9 the modified construction comprises recesses 16 in the ends of the parts 1 and 2 adapted to receive tongues 17 on the connecting part 3, whereby relative lateral movement of the parts 1 and 2 is prevented 55 when the ring is compressed.

The modified construction illustrated in Fig. 10 is identical with that illustrated in Figs. 6 and 7 with the exception that the ends of the parts 1 and 2 and the adjacent 60 portions of the connecting part 3 are cut radially and not obliquely.

The modified construction illustrated in Fig. 11 comprises tongues 18 on the ends of the parts 1 and 2 arranged to engage in 65 recesses 19 in the connecting portion 3 when

the ring is compressed. In this construction also there are shoulders 20 arranged to engage in recesses 21 to limit outward expansion of the ends of the parts 1 and 2 when the ring is compressed.

70

Other modifications will be apparent without specific illustration or description and it will be understood that I contemplate such variations as may be within the scope of the appended claims.

75

What I claim and desire to secure by Letters Patent is:—

1. A piston ring of the open resilient type, comprising two overlapping ring portions, each extending nearly the entire circumference of the ring and being of uniform width throughout their length, a relatively short connecting portion integrally connecting said ring portions, and shoulders on said ring portions arranged to engage with said connecting portion to hold the ends of the ring portions in proper annular alinement.

80

2. A piston ring of the open resilient type, comprising two overlapping ring portions of uniform width throughout their length, and having their adjacent side edges at right angles to the axis of the ring, a connecting portion integrally uniting said ring portions, oblique shoulders on the ends of said ring portions, and oblique shoulders on said connecting portion adapted to engage the shoulders on the ring portions to hold the ends of said ring portions in proper annular alinement.

90

3. A piston ring of the open resilient type composed of a single piece of metal comprising two overlapping parts extending nearly the entire circumference of the ring and having their abutting edges pressed together by the internal elasticity of the material, a relatively short connection integrally uniting said overlapping parts, and means for holding the ends of the overlapping parts in approximate annular alinement.

105

4. A piston ring of the open resilient type comprising a relatively short connecting portion and two overlapping ring portions integral with the connecting portion and each extending nearly the entire circumference of the ring and having a combined width equal to the width of the connecting portion, having their abutting edges at right angles to the axis of the ring, and held together by internal elasticity of the overlapping portions, and engaging shoulders on said overlapping portions and on said connecting portion respectively holding said overlapping portions in annular alinement.

115

5. A piston ring of the open resilient type comprising a connecting portion, two overlapping ring portions integral with the connecting portion and each extending nearly the entire circumference of the ring and

120

125

130

having a combined width equal to the width of the connecting portion and having their abutting edges at right angles to the axis of the ring, engaging shoulders on said 5 overlapping portions and said connecting portion respectively holding said overlapping portions in annular alinement, and tongue and groove connection between said overlapping portions and said connecting 10 portion limiting lateral movement of said overlapping portions relative to said connecting portion.

6. A piston ring of the open resilient type comprising an annular member composed of 15 a connecting portion and two overlapping ring portions having a combined width equal to the width of the connecting por-

tion pressed together by resiliency thereof and having their abutting edges at right angles to the axis of the ring, shoulders 20 formed on said overlapping portions engaging said connecting portion and holding the overlapping portions in proper annular alinement, and a connection between the overlapping portions and said connecting 25 portion limiting lateral movement of said connecting portion.

In witness whereof, I have signed this specification in the presence of two subscribing witnesses.

LEWIS WESTERHOUSE.
